UNITED STATES PATENT OFFICE.

MORRIS GOLDBERGER, OF CHICAGO, ILLINOIS, ASSIGNOR TO CRESCO-CREAMERY SUPPLY CO., OF CHICAGO, ILLINOIS, A CORPORATION OF ILLINOIS.

PASTEURIZER.

Application filed March 18, 1922. Serial No. 544,965.

To all whom it may concern:

Be it known that I, MORRIS GOLDBERGER, a citizen of the United States, and a resident of Chicago, in the county of Cook and State 5 of Illinois, have invented certain new and useful Improvements in Pasteurizers; and I do hereby declare that the following is a full, clear, and exact description thereof, reference being had to the accompanying 10 drawings, and to the characters of reference marked thereon, which form a part of this specification.

This invention relates to improvements in apparatus for treating milk for pasteurizing 15 the same under the known batch process of pasteurizing, or for otherwise conditioning milk and other liquids, and the invention consists in the combination and arrangement of the elements shown in the 20 drawings and described in the specification, and is pointed out in the appended claims.

An apparatus to which the improvements 25 constituting my invention is applied consists, in general terms, of a jacketed tank comprising an inner shell to receive the material to be treated, an outer supporting shell, with a space between them to receive a heating medium, such as water or steam, an agitator within the inner shell, and driving means 30 for turning the agitator to maintain the material in motion while being treated.

Among the objects of the invention is to provide an improved construction of such apparatus for solidly connecting the inner 35 and outer shells to constitute a rugged unitary structure, and by means including spacing elements to space the shells to produce the jacket space therebetween.

Another object of the invention is to provide 40 an improved driving mechanism support for the agitator so arranged as to cooperate with the mechanism for spacing the shells and for supporting the inner shell from the outer shell, both for the purpose of 45 firmly anchoring the driving mechanism support to the tank and for the purpose of bracing the structure.

Another object of the invention is to exteriorly insulate the outer shell by means 50 to avoid contact of the hand with a heated surface and also to produce an attractive exterior dressing for the apparatus.

A further object of the invention is to provide 55 an improved driving mechanism for use in connection with such tanks which is

simple in construction, sanitary in use, and which can be readily disconnected when the material to be treated is to be poured into the tank.

Other objects of the invention are to 60 otherwise improve and simplify apparatus for this general purpose.

As shown in the drawings:

Figure 1 is a vertical axial section, on line 1—1 of Figure 2, of an apparatus embodying my invention.

Figure 2 is a plan view thereof.

Figure 3 is a partial plan and partial sectional view, taken on the line 3—3 of Figure 1.

Figures 4 and 5 are enlarged sectional details, taken on the respective lines 4—4 and 5—5 of Figure 3.

The apparatus includes an open top tank 75 designated as a whole by 10, which comprises an outer shell 11 and an inner shell 12, which are spaced between their bottoms and sides to produce a space 14 to receive a heating or other fluid to control the temperature of the material to be treated in the 80 shell 12. The outer shell 11 may be made of boiler plate construction, suitably fabricated and of substantial strength. The inner shell 12 is made of lighter gauge sheet metal, preferably copper or like metal of 85 high heat conductivity.

The said tank is supported on legs 15, 15, which, as shown, consists of studs or short pipe sections that are threaded into bosses 16 fixed to the outer shell bottom and are 90 threaded at their lower ends into spherical bearers 17. The threaded connection of said bearers with the studs or stems of the legs enables the tank to be adapted to uneven surfaces while maintaining a proper liquid 95 level in the tank.

The said inner shell is supported by and centralized within the outer shell by means made as follows:

The upper, open end of the inner shell is 100 formed with an outwardly extending, radial, preferably continuous, flange 18. It is adapted to lie over the horizontal flange 19 of a ring 20 of angle cross section, the vertical flange 21 of which lies exteriorly 105 against and is riveted to the shell 12 below its terminal flange 19. The said shell flange and ring 20 constitute a reinforcement for the open margin of the said inner shell.

Fastened to the upper margin of the outer 110

shell 11 are a plurality of relatively short, angularly spaced, angle brackets 22, the vertical members of which are riveted or otherwise fastened to the shell 11 on the 5 inner side thereof, and the horizontal members 23 of which extend radially inwardly in underlapping relation to the horizontal flange 19 of the ring 20. Other relatively short, arcuate, angularly spaced, solid blocks 10 22' are arranged between the depending flange of the ring 20 and the inner side of the outer shell 11, and are riveted thereto, as shown in Figures 3 and 4. Said blocks 15 constitute spacers along with the interspersed brackets 22 to space the inner from the outer shell at the open, upper ends thereof. They also assist to support the inner shell, being arranged with their top surfaces at the level of the upper members of 20 the brackets 20. Said spacing blocks 22' serve additionally to constitute a connection between the tank and a driving mechanism supporting beam 36, as will hereinafter more fully appear. The upper or end edge of the 25 jacketed tank thus formed is finished and forms a neat, water-proof joint by a thin channel cross section finishing ring 20' that is fitted with its intermediate portion over the flange 18 and with its side legs against the inner side of the shell 12 and the outer 30 side of the shell 11. Said finishing ring is adapted to be removably fixed to the inner shell by a smooth, solder joint, which permits said ring to be readily removed when 35 occasion requires, by applying a blow torch to the soldered connection and rolling the finishing ring upwardly away from the tank top edge. This construction enables the inner shell to be readily removed for the purpose of repairing it with a minimum disturbance to the structure that supports the shell. The construction described produces 40 at the open top of the inner shell a continuous annular flange 19 which rests on the supporting members 23 of the brackets 22 and said blocks 22' to thereby firmly support the inner shell from the outer shell.

The inner shell is provided centrally at its 45 bottom with a short drain tube 24 which is fastened to said inner shell in any suitable manner, as by being provided with a head 25 which is seated in a recessed part of the bottom of the inner shell. Said tube extends through the space 14 and an aligned opening 50 in the bottom of the outer shell. The tube is exteriorly threaded to receive below the bottom of the shell 11 a clamping nut 26, which, when turned upwardly on said threaded tube, draws the inner shell downwardly 55 and forces the flange 19 of the ring 20 firmly on the shoulders or seats, constituted by the brackets 22 and blocks 22', in a manner to centralize and join the inner and outer shells together to constitute a rugged unitary structure with the intervening space 14. A sec-

ond nut 27 is threaded to said tube within the space 14 to bear against the upper face of the bottom of said outer shell 11 to co-operate with said tube and the nut 26 to brace the inner from the outer shell. Access 70 to the nut 27 may be had through a hand hole covered by a suitable plate 29, as shown in Figure 1. 30 designates a supply pipe to furnish a heated medium, as water and steam, to the space 14, and an overflow pipe 75 31 near the top of the tank furnishes drainage for the water and steam or other heating agent. 32 is a drain pipe for draining water from the space 14.

The contents of the tank is adapted to be 80 stirred by an agitating device comprising, as shown, a vertical rotative shaft 33 provided with one or more pairs of blades 34. The upper end of said shaft is mounted to rotate in a vertical bearing sleeve 35 which is fixed 85 to the broad, horizontal beam 36 which extends across the top of the tank and is supported on the rim thereof. Said bearing extends below and above the bottom to afford an ample length of bearing between the shaft 90 and sleeve. The shaft is provided above said bearing with a belt pulley 37. Said pulley 37 is connected by a belt 38 to a pulley 39 which constitutes part of a suitable driving mechanism enclosed in a gear box 40. As 95 shown, said pulley 39 is fixed to the upper end of a shaft that is geared to a horizontal shaft 41 mounted in the walls of the gear box 40, and one end of the shaft extends beyond said gear box to receive tight and loose pulleys by which exterior driving power is transmitted to said driving gear. The said gear box 40 is fixed to one end of the beam 36 by means of an L-shaped bracket 43 bolted to the beam and to the gear box, as shown in 100 Figure 4.

The said beam 36 is much wider than the diameter of the pulley 37, so that the belt 38 lies well within the side margins of the beam, as best shown in Figure 2. This arrangement prevents dirt which may collect on the belt or on the pulley 37 from dropping into the tank, the beam being in position to receive particles dropping from the belt and pulley. An advantage, in the pasteurizing 110 art, of the agitator drive and its support, including the belt and the pulley of the agitator shaft, is that the belt can be removed from the pulley at a time when one or more of the top covers 10', fitted to the top of the 115 tank between said beam and the top edge of the tank, is removed for pouring material into the tank.

The said beam 36 is attached to the rim of the tank by bolts 44 which extend through the ends of the beam, the overlapping members 20, 18, 19, and 23, and into the solid spacing and reinforcing blocks 22'. This connection of the beam to the tank 120 structure performs the correlated functions 125 130

of reinforcing and spacing the shells, due to the blocks 22', bracing the tank structure at its top by the use of the wide beam extending across the top of the tank and securely attached to the finished edges by numerous bolts (Figure 3), affording a rigid connection of the gear box to the structure, and providing a guard to prevent foreign particles falling from the driving

10 mechanism into the tank when open. A further advantage of the structure is its freedom from projecting parts or roughened surfaces likely to collect dirt, and the ease by which the apparatus may be cleaned.

15 The structure is a sanitary one and has the further advantage of an attractive product.

It will be noted from an inspection of Figure 3 that the spacing and beam anchoring blocks 22' are arranged in two pairs, 20 with the blocks of a pair at opposite sides of the tank top, and with the several blocks angularly spaced ninety degrees around the circumference of the top. This construction and arrangement of the parts make it convenient to dispose the agitator and the driving gear supporting beam in either of two transverse positions across the tank top and to thereby readily adapt the apparatus as a whole to different locations of pipe connections

30 from the tank and to an exterior source of driving power. Thus by detaching the beam 36 from the tank it may be adjusted thereon to bring the gear box at any one of four different points on the rim 35 of the tank, and thereby, without the necessity of disturbing fixed pipe connections, adapt the pulleys of the gear box to power belts which approach the apparatus from different directions.

40 In order to avoid burning the hands of an operator by contact with the side of the shell 11, a relatively thin sheet 45 of metal surrounds the principal upright part of said shell. Said sheet may become part of an insulator by spacing it from the outer shell 11 by upper and lower insulating spacing rings 47, 48 respectively, or by filling such space with a layer 48' of suitable insulating material. When said insulating sheet is employed its upper margin lies between the upper insulating ring and the outer depending member of the finishing ring 20'.

I claim as my invention:

1. Apparatus for the purpose set forth 55 comprising an open top jacketed tank, with cover means therefor, said tank being composed of inner and outer shells, with means at the tank top for spacing the shells and for reinforcing the tank structure thereat 60 and for supporting the inner shell on the outer shell, a beam extending across the top of the tank and fixed to said spacing, reinforcing and supporting means, and provided with a bearing for an agitator shaft, 65 an agitator shaft rotatively mounted in said

bearing and a driving gear mechanism for said shaft, embracing a gear supported on said beam outwardly beyond the open top of the tank, and a connection between said gear mechanism and said shaft located over 70 and between the planes of the side edges of the beam.

2. Apparatus for the purpose set forth comprising an open top jacketed tank, with cover means therefor, said tank being composed of inner and outer shells, with means at the top of the tank for spacing the shells and for reinforcing the tank structure thereat and for supporting the inner shell on the outer shell, a beam extending across the top of the tank and fixed to said spacing, reinforcing, and supporting means and provided with a bearing for an agitator shaft, an agitator shaft rotatively mounted 75 in said bearing, embracing a gear box supported on said beam outwardly beyond the open top of the tank, said driving mechanism including a pulley, a pulley on the agitator shaft above said beam, and a belt 80 trained over and removable from said pulleys and disposed between the planes of the side edges of said beam.

3. Apparatus for the purpose set forth comprising an open top jacketed tank, with cover means therefor, said tank being composed of inner and outer shells, said inner shell being provided at its top with a radial, outwardly extending reinforced flange, and the outer shell being provided with internal, 100 fixed shell spacing and reinforcing and inner shell supporting member, engaging said flange and an agitator shaft and agitator driving mechanism supporting beam extending across the top of the tank and fixed at 105 its ends to said shell spacing and reinforcing means.

4. Apparatus for the purpose described comprising a jacketed tank, including inner and outer spaced shells, the inner shell being 110 provided at its top with a radial, outwardly extending, reinforced flange, shell spacing elements attached to the outer shell beneath and supporting said inner shell through said reinforced flange, a plurality of said elements being diametrically spaced and solid, an agitator shaft and driving mechanism supporting beam extending across the top of the tank, and screw bolts extending through said beam, through said flange and 120 threaded into said solid supporting and spacing elements.

5. Apparatus for the purpose described comprising a jacketed tank, including inner and outer spaced shells, the inner shell being 125 provided at its top with a radial, outwardly extending, reinforced flange, shell spacing elements attached to the outer shell beneath and supporting said inner shell through said reinforced flange of the inner shell, a channel 130

shaped finishing ring fitted over the rim of the tank thus formed and fixed thereto, an agitator shaft and driving mechanism supporting beam extending across the top of the tank, and screw bolts extending through said beam and through said finishing ring and reinforced flanges and threaded into the solid spacing and supporting elements.

6. Apparatus for the purpose set forth
10 comprising a jacketed tank, including inner and outer spaced shells, with shell spacing and supporting means at the top of the tank comprising a radial flange on the inner shell, a ring of angle cross section surrounding and
15 fixed to the inner shell and with one of its members beneath and reinforcing the flange of the inner shell, supporting and spacing elements fixed to and extending inwardly from the outer shell on which the radial
20 flange of said reinforcing ring bears, and means connected between the bottoms of the tanks centrally thereof for exerting tension of the inner shell to force the reinforced flange of the inner shell against said supporting members and for centralizing the inner shell and bracing it with respect to the outer shell.

7. Apparatus for the purpose set forth
comprising a jacketed tank, including inner
30 and outer spaced shells, with shell spacing and supporting means at the top of the tank comprising a radial flange on the inner shell, a ring of angle cross section surrounding

and fixed to the inner shell and with one of its members beneath and reinforcing the 35 flange of the inner shell, supporting and spacing elements fixed to and extending inwardly from the outer shell on which the radial flange of said reinforcing ring bears, and a thin, flexible, metal, channel shaped 40 ring fitted over the tank rim and with one member thereof soldered to the inner face of said inner shell.

8. Apparatus for the purpose set forth comprising a jacketed tank, including inner 45 and outer spaced shells, with shell spacing and inner shell supporting means at the top of the tank, a relatively narrow beam extending across the top of the tank and fixed at its ends to the shell spacing means, 50 segmental cover members for the tank at the sides of said beam, each separate from and independently movable with respect to the beam, an agitator in the tank embracing an upright shaft mounted in a bearing carried by the beam, a driving mechanism for said shaft, embracing a drive member supported on said beam outwardly beyond the open top of the tank, and a driving connection between the drive member and said shaft 55 arranged above and between the planes of the side edges of said beam.

In witness whereof I claim the foregoing as my invention, I hereunto append my signature this 15 day of March, 1922.

MORRIS GOLDBERGER.
